[57] CLAIM

The ornamental design for a time capsule, as shown.

DESCRIPTION

FIG. 1 is a front elevational view of a time capsule showing my new design;

FIG. 2 is a rear elevational view; and,

FIG. 3 is a right side elevational view, the opposite side being identical.

It is to be noted that those parts of the time capsule shown cross-hatched are of a material or materials which contrast with the remainder of the time capsule.
